UNITED STATES PATENT OFFICE.

JOHN W. DARLEY, JR., OF BALTIMORE, MARYLAND.

THREAD-GUARD FOR SEWING-MACHINES.

1,139,261.

Specification of Letters Patent.

Patented May 11, 1915.

Application filed April 6, 1910. Serial No. 553,772.

To all whom it may concern:

Be it known that I, JOHN W. DARLEY, Jr., a citizen of the United States, residing at Baltimore, in the State of Maryland, have 5 invented certain new and useful Improvements in Thread-Guards for Sewing-Machines; and I do hereby declare the following to be a full, clear, and exact description of the invention, such as will enable others 10 skilled in the art to which it appertains to make and use the same.

My invention relates to improvements in thread guards for sewing machines, and is especially designed for sewing machines 15 used for attaching buttons to garments, but it is not restricted to this class of sewing machines, as it is capable of general application.

In ordinary sewing machines, occasionally 20 the loop formed in the needle thread is not properly caught by the shuttle. After the needle goes through the goods and commences to return, a loop is formed on the side of the needle adjacent to the shuttle, which is intended to be caught by the hook on the 25 shuttle and drawn over the shuttle. In order to provide thread for this operation, the take-up at the same time moves toward the shuttle. If, as occasionally happens, the hook on the shuttle fails to catch the loop, 30 the looseness of the thread, which is normally provided so that the thread may be freely carried around by the shuttle, is not compensated for and the thread hangs loose 35 in the air. This is apt to cause tangling and breaking of the thread as the take-up moves back. In the case of button sewing machines, on the first stitch the needle thread is carried through the fabric and is held by 40 holding means, and it is only on the second stitch that the needle thread is carried completely around the shuttle. The take-up device, however, moves toward the shuttle 45 during the first stitch as well as during the other stitches, leaving a looseness in the thread during the first stitch, which, as before explained, is liable to cause tangling and breaking as the take-up moves back. By my invention, however, all these difficulties, incident either to button sewing machines or the ordinary sewing machines, are 50 removed.

With the objects stated in view, my invention consists in the construction and combinations of parts as hereinafter described and claimed.

In the accompanying drawings—Figure 1 represents a button sewing machine in side elevation, parts being omitted. Fig. 2 is a front view of the same, on a larger scale, 60 showing my invention applied to the end of the machine. Fig. 3 is a perspective view of the thread guard, shown detached.

1 represents a sewing machine of a standard type with my improved thread guard 65 applied thereto. It is provided with the usual mechanism for operating the needle, shifting the work and the button, and operating the shuttle, which parts need not be specifically described. It is also provided 70 with the usual starting, stopping, and operation governing devices, as set forth in my application, Serial No. 570,857 filed July 7, 1910, which require no specific description here. In the machine shown in the drawing, 75 however, a bell crank lever 2, adapted to be operated by a wire 3, attached to a pedal in the ordinary manner, is shown, for the purpose of starting the machine.

4 represents the front end of the machine, provided with the usual guides, in which the needle 5 is reciprocated, and also provided with a standard tension device 6 and a standard take-up 7. To the front end of the part 4 is attached the thread guard, 80 which consists of a funnel-shaped portion 8, having a flat rear part 9, and tapering downwardly to a small perforated end 10. The rear part 9 is slotted, as shown at 11, and on each side of this slot are mounted 85 curved guards 12, each in the form of a segment of a circle struck from the center of motion of the take-up 7, said guards being spaced apart to provide for the motion of the take-up and preventing the 90 loose thread from flying up over the end of the take-up.

Around the lower end of the part 8 is arranged a wire guide 13, through which the thread passes. In the side of the part 100 8 is secured a hardened steel plate 14, provided with a central perforation, through which the thread is passed. The hole in this small plate 14 is so arranged that the thread, after being passed over the tension 105 device, will pass in practically a straight line to the hole in the take-up lever, when the latter is in its highest position.

The rear portion 9 has an extension 15, which is arranged substantially parallel to 110 the portion 9, and is provided with perforations in which are located screws 16,

which fasten the whole thread guard to the front of the machine. This extension has a forwardly extending curved rib 17 on one edge. The curved part 8 is made integral with the part 9 on the line 18, but does not closely fit this part on the other edge, for, as shown at 19, there is a space left to permit the passage of the thread during the threading operation. The curved side 17 is to prevent the loose portion of the thread from being entangled, if it should fly out through the space 19. The wire guide 13 is bent around so as to form a complete circle 20, and the end 21 is bent upwardly and loosely bears against the part 8 for convenience in the threading operation, as hereinafter described. The free end of this wire is made long enough and caused to engage with the part 8, so as to prevent the looseness in the thread from being entangled around the end of the wire. The part 15 tapers downwardly to its lower end and is provided with a smaller curved side 22, making a trough through which the thread passes. This prevents the looseness of the thread from working backward and getting entangled in the needle bar and contiguous parts. The thread, after passing downwardly beyond the thread guard, is passed behind the spring portion 23, of standard construction, by the needle bar, and then down through the hole in the end of the needle.

The button is supported in a button holder of any approved construction, which is not shown in the drawing. The fabric is held between the plates 24 and 25, which with the button chuck are vibrated by the cam 26 in the usual manner, so that the needle will pass through the holes of the button at the proper time. The shuttle is supported below the plate 25 in the usual manner, and operates in the usual way.

The operation of threading is as follows: The thread from the spool is passed through the hole 39, then down and around the tension device 6, then through the hole in the plate 14, up through the hole in the end of the take-up device 7. It is then passed through the opening 19 and is drawn down and around the lower portion of the wire 13, and passed upwardly and slipped between the free end of said wire and the side of the part 8, and drawn down again, whereupon it passes through the circular portion 20 of the wire. It is then slipped behind the spring plate 23 and downwardly through the hole in the point of the needle. This spring plate 23 is adapted to grip the thread and release it at the proper times, this operation being accomplished by well known means. The operations of threading the shuttle and of sewing on a button have nothing to do with this particular invention, and need not be specifically described,

these operations being accomplished in a well known manner. When the machine is at rest, at the beginning of the operation, the parts are in the position shown in Figs. 1 and 2. The operator, after introducing the fabric and the button into the machine in the well known manner, places his foot upon the treadle, which pulls down the wire 3 and starts the machine, which is operated by power, into operation. The needle starts downward, carrying the thread, and reaches its lowest position. The needle then starts to rise, forming a loop in the needle thread in the well known manner, and the point of the shuttle hook enters this loop in the well known manner, and the further movement of the shuttle pulls down the free end 40 of the needle thread through the hole in the throat plate. During this downward movement, the spring plate 23, which is operated by well known means, clamps the needle thread, so that the thread cannot be pulled through the hole in the end of the needle toward the shuttle, thus causing the shuttle to pull the end 40 of the thread down through the hole. The needle then continues to rise, the end 40 of the thread being still passed down through the hole, and the take-up device, having moved downwardly, causes a looseness in the thread, which, by the means already described, is prevented from becoming entangled with any of the moving parts. The sewing then continues, and during the second stitch and at about the time when the shuttle hook engages the loop in the needle thread, the spring plate 23 is disengaged from the thread, so that the needle thread may be moved freely under the spring plate 23 and passed over the shuttle without resistance, while the take-up device is coming down. The spring plate 23 is kept disengaged from the thread until almost at the end of the sewing operation, as hereinafter explained.

I claim:—

1. In a sewing machine, the combination of the frame of the machine, a tension device carried thereby, a take-up device, a needle, means for operating said take-up device and needle, and a thread guard attached to one end of the frame, and through which the needle thread is adapted to pass, including a funnel-shaped portion having a hole in one side, and parts between which said take-up device reciprocates, substantially as described.

2. In a sewing machine, the combination with the machine frame, a needle, a take-up device and means for operating them, of a thread guard secured to one end of the frame, and provided with a slot therein, through which said take-up device reciprocates, and with curved protecting portions on each side of said slot, said thread guard being made of sheet metal bent into an ap-

proximately funnel-shaped form, substantially as described.

3. In a sewing machine, the combination with the frame of the machine, a take-up device, a needle and means for operating them, with a thread guard of sheet metal secured to said frame, said guard being in the main funnel-shaped, with a lower open end, and provided with a hole through which the 10 thread enters, with a slot having guard plates in proximity thereto, through which

slot the take-up device works, with a space through which the thread may be slipped, and a wire guide attached to said guard, substantially as described.

In testimony whereof, I affix my signature, in presence of two witnesses.

JOHN W. DARLEY, JR.
